(57) **CLAIM**

The ornamental design for a clip-on fan, as shown and described.

DESCRIPTION

FIG. 1 is a front and right side perspective view of a clip-on fan showing my new design;

FIG. 2 is a rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front and right side perspective view thereof, in an alternative state; and,

FIG. 10 is a front and bottom perspective view thereof, in another alternative state.

The broken lines in the drawings depict the portions of the clip-on fan that form no part of the claimed design.
